UNITED STATES PATENT OFFICE

107,268

DESIGN FOR AN AUTOMOBILE

Clifford Brooks Stevens, Milwaukee, Wis., assignor to William Woods Plankinton, Milwaukee, Wis.

Application November 9, 1936, Serial No. 65,798

Term of patent 14 years

To all whom it may concern:

Be it known, that I, Clifford Brooks Stevens, a citizen of the United States, residing at Milwaukee, in the county of Milwaukee and State of Wisconsin, have invented a new, original, and ornamental Design for an Automobile, of which the following is a specification, reference being had to the accompanying drawing, forming part thereof.

In Figures 1 and 2, the solid black is used for shading and not to show contrasting color.

I claim:

The ornamental design for an automobile, as shown and described.

CLIFFORD BROOKS STEVENS.
